CLAIM

The ornamental design for a display device, as shown and described.

DESCRIPTION

FIG. 1 is a front side view of a display device in accordance with the present invention;

FIG. 2 is a back side view of the display device depicted in FIG. 1;

FIG. 3 is a left side view of the display device depicted in FIG. 1;

FIG. 4 is a right side view of the display device depicted in FIG. 1;

FIG. 5 is a top view of the display device depicted in FIG. 1;

FIG. 6 is a bottom view of the display device depicted in FIG. 1; and,

FIG. 7 is a front side perspective view of the display device depicted in FIG. 1.

The broken lines shown in the drawings illustrate portions of the display device and form no part of the claimed design.

1 Claim, 5 Drawing Sheets
